MEANS FOR MOUNTING A RAIL

William J. Ronan, Detroit, Mich., assignor to Safety Bath Rail, Inc., Dearborn, Mich.

Application July 29, 1955, Serial No. 525,298

10 Claims. (Cl. 248—251)

This invention relates to a spring locking assembly for automatically clamping sections when forced together.

The object of my invention is to produce a special bath-tub safety arm mounting adaptable for application either before, or after, the bath-room wall construction.

Another object is to produce a safety arm support that can be easily, and rigidly mounted on any bath-room wall stud.

A further object is to provide a rigid arm support unit that may be easily pressed in place, automatically engaging adjoining members so as to rigidly lock in any adjusted wall position.

A still further object is to provide a safety arm mounting that is simple in construction, easily and efficiently applied, and that can be manufactured at a very low cost.

These several objects are attained in the preferred form by the construction and arrangement of parts as are more fully hereinafter set forth and defined.

Similar parts on all drawings are marked by similar numeral or letters.

Fig. 1 is a plan view of my new device, showing the exterior form and assembly when mounted on a bath-room wall.

Fig. 2 is a side elevation of the same casing assembly showing the relative position of the inclosed tubular bath-tub safety arm section.

Fig. 3 is a cross-sectional view taken on the line 3—3 of the Fig. 1, showing the general arrangement of the various assembled sections and spring lock means.

Fig. 4 is a detail elevation of the support thimble as mounted within the outer conical casing unit.

Fig. 5 is an end view of the support thimble shown in the previous Fig. 4, showing the tubular formation of the cylindrical member.

Fig. 6 is a detail side elevation of the safety arm spring lock support member.

Fig. 7 is an end view of the Fig. 6, showing the split tubular section formation, and the projected spring lock teeth formed thereon.

Fig. 8 is a side elevation of the combination lag and lock screw mounting unit.

Fig. 9 is a bottom view of the conical mounting casing, showing the circular casing unit design.

Fig. 10 is likewise the top view of the same mounting casing, showing the general exterior design and the central mounting recess formed through the top wall.

Fig. 11 is a cross-sectional view of a device similar to Fig. 1 but having modified spring lock means shown in closed position.

Fig. 12 is a cross-sectional view as in Fig. 11 but showing the lock means in open position.

Fig. 13 is an elevation view of the support thimble as is mounted within the support casing outer end circular recess.

Fig. 14 is likewise a side elevation of the modified threaded spring lock support as inserted therein.

In general, my invention comprises a special combination mounting stud bolt, formed with lag screw

threads on one end thereof, and special lock screw threads on the opposite bolt end, designed for rigidly mounting same within a bath-room wall stud, positioned therein as above and adjacent to a bathtub. The stud bolt is rigidly mounted at right angles to said wall stud, projecting the special lock thread section outward for a predetermined length, and is inclosable within a smooth wall casing thimble, and special engaging snap-lock unit designed for pressure insertion, and formed with a safety arm clamp member projected therefrom.

I will now describe more fully the detail construction of my improved mounting unit, referring to the drawings and the marks thereon.

The combination lag-lock screw 1 is made of a suitable metal rod, of predetermined size and length, and is formed with lag screw threads *a* extended for about one third the length, suitable for rigidly mounting same within a wood stud 2 section in the ordinary manner, as illustrated in the Fig. 1 of the drawings. The lag-lock screw 1 is positioned at right angles to the vertical stud wall, and projected therefrom for a predetermined length. On the projected outer screw end are formed special lock threads *b*, preferably designed straight, vertical inner thread walls, and with sloping outer thread walls, as illustrated in the Fig. 8 of the drawings, said lock threads being extended nearly the full projected screw section length. Over the projected lock screw section is mounted a smooth inclosing casing 3, preferably of a bell-shaped, or conical, design, and is formed with a closed top end *c* through which a circular recess *d* is provided. Within the bell-shaped casing top circular recess *d* is mounted a flanged tubular support thimble 4 tightly fitted therein, positioned concentric with said casing axis. Within the support thimble central tubular recess *e* is slidably mounted a spring lock arm support clamp 5 formed of an open circular safety arm clamp band *f*, having semi-tubular slide lock sections *g* projected externally from opposite ring ends, positioned parallel with each other, and engageable with the support thimble inner tubular recess *e* and the inclosed lag-lock screw section. Within the walls of the projected tubular section arm clamps *f* are formed special latch teeth *h*, stamped, or cut free at the inner ends thereon, and pressed within said tubular lock slide sections *g*, forming spring lock teeth *h*, then positioned engageable with the lag-lock screw threads *b*, at any position when forced thereover as the support clamp is forced thereover. When the clamp 5 is tightly pressed within the thimble 4 and over the lag screw 1, it becomes a rigid locked support unit for any inserted bath-tub safety rail, as may be mounted therein. The slide lock sections *g* are firmly locked within the support thimble 4 by means of two standard set-screws 8, 9 threadably mounted through the support thimble 4 walls.

For special bathtub safety arm mountings, requiring removal at times, a modification of the inner clamp locking threads and connecting means, may be substituted for the spring lock teeth *h*, as is illustrated in the Figs. 11 and 12 of the drawings, and where both teeth *h* and lock threads *b* may be substituted by plain V-shaped threads *m* and *n* as illustrated in the Figs. 11 and 12, with the lock slide sections *g* threaded internally by ordinary thread means, but of an internal thread diameter to allow sliding over the inclosed lag-lock screw 1, for inserting within said support thimble 4 a predetermined length before engaging the tapered thimble lock slides *p* and closing same over the inclosed stud lock threads *n* as illustrated in the Fig. 12, and by rotation of the surpressed clamp unit on the engaged threads the connecting clamp units are tightly drawn together by the ordinary reaction of the thread engaging means, to a closed locked position as illustrated in the Fig. 11 of the drawings. Removal of

the lock clamp unit may be accomplished by the reverse rotation of the unit.

It will be observed from the foregoing that I have provided a means for mounting a rail A horizontally adjacent a wall behind which is a stud 2. The means comprises an elongated bolt 1 having an end *a* formed with threads whereby it may be secured to and thus mounted on the stud and thus on the wall with the bolt projecting at right angles to the wall. The bolt further has an exposed part whose side surface is formed with a series of closely and longitudinally spaced peripheral projections. These may be ribs *b* of Fig. 8 or threads as shown in Fig. 12. The mounting means further comprises a sleeve 4 positioned axially over the exposed part of the bolt and having a flange. Included also is a conical bell 3 positioned axially over the sleeve 4 and the bolt 1 and disposed between the wall and the sleeve flange, the bell having on its smaller outer end an aperture receiving the sleeve. The mounting means further comprises a U-shaped clamping band, Fig. 6 or Fig. 14, having its bight *f* looped for receiving the rail A and having parallel legs *g* or *g'* disposed within the sleeve and also positioned axially over the bolts. The sleeve flange is between the bell and the loop *f*. The inner surfaces of the band legs *g* have a series of closely and longitudinally spaced inward projections complementing those of the bolts for interlocking cooperation with them, these projections being shown at *h* in Fig. 7 and they may also be in the form of internal threads *n* of Fig. 14. The sleeve has means for biasing the legs of the band laterally against the bolt and thus biasing the projections of these legs into interlocking cooperation with the projections of the bolt. Such biasing means may comprise the set screw 9 in the sleeve flange which passes transversely through that flange outside the bell and engages a leg of the band.

The biasing means may also be in the form of a taper *p* of Fig. 13 such as a tapered shoulder at the inner end of the sleeve 4 and cooperating tapered inner ends as shown in Fig. 14 of the band legs.

Having fully described my spring grip lock mounting for bathtub safety arm, what I claim as my invention and desire to secure by Letters Patent is:

1. For mounting a rail horizontally adjacent but spaced from a vertical wall, an elongated bolt having its inner end formed to be secured to and thus mounted on said wall with the bolt projecting at right angles to said wall, the bolt having its other outer end exposed, a centrally bored sleeve positioned axially over the exposed end of the bolt and having on its outer end a flange, a conical bell separate from the sleeve and positioned axially over the exposed end of the bolt and having its smaller end formed with a central aperture removably receiving the sleeve and positioned between the wall and the sleeve flange, and a clamping band formed of thin springy metal and having a looped bight arranged outside the sleeve flange for receiving the rail and having a pair of parallel legs of arcuate cross section integral with the bight and disposed within the sleeve and positioned axially over the exposed end of the bolt which is thus between it and the sleeve, and clamping means on the sleeve which squeezes the legs of the band towards each other and towards the bolt to clamp these legs against the bolt.

2. A construction according to claim 1, wherein said means comprises a set screw threadedly engaged with and passing transversely through the sleeve and contacting the surface of one leg, which surface is closest to the sleeve, the set screw being arranged to press said leg towards and into contact with the bolt.

3. A construction according to claim 1 wherein the means comprises a portion of the inner surface of the sleeve biasing the band legs towards each other and against the bolt.

4. A construction according to claim 1 wherein the means comprises a tapered shoulder at the inner end of the sleeve which reduces the diameter of the sleeve bore and which contacts the inner ends of the band legs to bias them towards each other and against the bolt.

5. A construction according to claim 1 wherein the adjacent surfaces of the band legs and the sides of the bolt are formed with cooperating toothed formations adapted to interlock with one another for interlocking the band to the bolt, under clamping action of the clamping means, against separation from the bolt in a direction away from the wall.

10 6. A construction according to claim 1 wherein the adjacent surfaces of the band legs and the sides of the bolt have cooperating toothed formations which interlock with one another for interlocking the band to the bolt, under clamping action of the clamping means, against separation from the bolt in a direction away from the wall; with the means comprising a set screw 15 threadedly engaged with and passing transversely through the sleeve and contacting a band leg and pressing the band leg into contact with the bolt.

20 7. For mounting a rail horizontally adjacent to but spaced from a vertical wall, an elongated bolt having one end formed to be secured to and thus mounted on said wall with the bolt projecting at right angles to said wall, the bolt having a part thereof exposed, with the side surface of the exposed part of the bolt being formed with a series of closely and longitudinally spaced toothed 25 30 35 40
